UNITED STATES PATENT OFFICE.

GEORGE W. PRENTICE, OF PROVIDENCE, RHODE ISLAND.

GLOVE-FASTENING.

SPECIFICATION forming part of Letters Patent No. 321,050, dated June 30, 1885.

Application filed December 31, 1884. (No model.)

To all whom it may concern:

Be it known that I, GEORGE W. PRENTICE, a citizen of the United States, residing at Providence, in the county of Providence and State of Rhode Island, have invented certain new and useful Improvements in Gloves; and I do declare the following to be a full, clear, and exact description of the invention, such as will enable others skilled in the art to which it appertains to make and use the same, reference being had to the accompanying drawing, and to the letters and figures of reference marked thereon, which form a part of this specification.

15 My invention relates to a new and novel improvement in gloves.

The objections to the various devices in present use for securing the wrist of a glove are well known. The buttoned glove has no means 20 of adjustment to the different sizes of wrists, while lacing-hooks are liable to catch into laces or other articles of apparel, causing serious annoyance.

My present invention has for its object to 25 provide a glove with a wrist-opening which can be readily adjusted to any size and with no projections to interfere with articles of apparel when in contact.

To this end my invention consists in 30 structuring the wrist of a glove with a series of straps on one side of the wrist-opening, and a corresponding series of buckles or clasps on the opposite side, whereby the said wrist-opening of the glove may be drawn together 35 and confined, substantially as hereinafter more fully described, and particularly pointed out in the claims.

In the accompanying drawing, the figure 40 represents a plan view of a glove embodying my improvement, the lower portion of the wrist-opening being secured, the remainder loose.

In carrying out my invention the edge A of 45 the wrist-opening of the glove is provided with a series of straps, *a*, secured thereto, the opposite side B being provided with a corresponding series of buckles or clasps, *b*, to engage the straps *a*. The straps are made of leather or other suitable material corresponding in color 50 or shade to that of the glove; or, if desired, a pleasing effect may be obtained by using straps of other shades than the glove, making a decided contrast.

Buckles, clasps, or other equivalent devices

may be employed which will retain the straps 55 when engaged therewith, the same being herein designated as buckles.

To prevent the straps from injuring the flesh of the wearer I secure a fly or gore, *d*, to one side of the wrist-opening; or, if preferred, it 60 may be secured to both sides, allowing sufficient expansion for the entrance of the hand through the wrist of the glove.

When the glove is in place on the hand, the straps are engaged with the buckles, the wrist-opening being closed to snugly embrace the 65 wrist and arm of the wearer, the buckles retaining the straps.

In place of a series of straps on one side and buckles on the opposite, I may make the glove 70 with an alternate series of straps and buckles on each side of the wrist-opening. The number of straps and buckles used is determined by the length of the wrist of the glove, the best result being attained by a closely-strapped 75 wrist.

From this description it will be seen that the wrist-opening of a glove provided with a series of straps and buckles in the manner described may be secured with ease and rapidity, 80 the strain on the wrist of the glove being borne equally by all the straps and buckles. There are no projections to catch into or injure articles of apparel when in contact, and the glove is readily adjusted to the difference in the 85 sizes of persons' wrists.

The straps for a glove being, necessarily, of very thin material, I have provided them with tags or clips on their ends to prevent their curling or fraying, as clearly shown at C in 90 the drawing.

Having described my invention, I claim—

1. As an improved article of manufacture, a glove provided with a series of straps, each strap provided with a metal clip or tag on its 95 end and buckles at the wrist-opening, substantially as set forth.

2. The combination, in a glove provided with a wrist-opening and a fly or gore secured thereto, of a series of straps and buckles secured at opposite sides of the said opening, substantially as set forth.

In testimony whereof I affix my signature in presence of two witnesses.

GEORGE W. PRENTICE.

Witnesses:

F. A. SMITH, Jr.,

CHARLES GREENE.
